STARTING SWITCH

Frank P. Gasser, Beverly Farms, Mass., assignor
to Gasard Patents Inc., New York, N. Y., a cor-
poration of New York

Application April 16, 1943, Serial No. 483,253

4 Claims. (Cl. 200—122)

1

This invention relates to starting switches for electric discharge lamps. More particularly the invention pertains to a switch of the character described in which at least one of a pair of contacts is carried by a bimetallic element.

Fixtures for fluorescent electric discharge lamps are usually provided with sockets for starting switches. These sockets are so arranged in the fixtures that both the diameter and height of the switches are limited to small dimensions. As a result, much difficulty has been experienced in so designing the switches that, despite their small size, the starting contacts may be rapidly opened after the lamp filaments have been raised to incandescence in order to quench sparking more rapidly and obtain a maximum surge voltage.

Another difficulty has been that the distance between the bimetallic strip and the heating means therefor changed during operation of the switch and adversely affected the heat transfer. Heretofore, complicated configurations of the strip have been resorted to for overcoming such difficulty, but these configurations have considerably increased the manufacturing and assembly costs of the switches.

It is an object of my invention to provide an improved switch of the character described in which the bimetallic element is so shaped and the heating means so constructed and arranged relative to the bimetallic element that the contact carried by the element is rapidly moved without affecting heat transfer.

Another object of my invention is to provide a switch of the character described which comprises relatively few and simple parts, is easily fabricated, durable and efficient to a high degree.

Other objects of this invention will in part be obvious and in part hereinafter pointed out.

The invention, accordingly, consists in the features of construction, combinations of elements, and arrangement of parts which will be exemplified in the construction hereinafter described, and of which the scope of application will be indicated in the appended claims.

In the accompanying drawing, in which is shown one of the various possible embodiments of this invention.

Fig. 1 is a schematic circuit diagram for a fluorescent electric discharge lamp with the starter switch embodying my invention shown in perspective;

Fig. 2 is a sectional view of the switch taken substantially along the line 2—2 in Fig. 1; and

Fig. 3 is a top plan view of said switch.

Referring now to the drawing, I have there

2

shown a fluorescent electric discharge tube 10 of a standard type comprising an elongated pellicid vitreous envelope 12 which is internally coated with a suitable luminescent composition, such as a mixture of phosphors. The tube is filled with a gaseous ionizable medium at a proper pressure, the ends are sealed off. Two spaced filamentary electrodes 14 are enclosed within the tube. These electrodes may be fashioned from or coated with material which will emit electrons when raised to an elevated temperature of or approaching incandescence.

Said tube 10 is of a type adapted to be used in a fixture and with an electric supply and starting circuit requiring the use of a four-terminal starting switch such as the switch 16 which embodies my invention. One of the electrodes 14 is connected to a terminal 18 of a power source, such as an alternating current line, through a lead-in wire 20, in which there is series-connected a standard, manually operated switch 22 and a ballast reactor 24. The other power terminal 26 is connected by a lead-wire 28 to one terminal 30 of my improved starting switch. The diametrically opposite terminal 32 of said switch is connected by a lead-wire 34 to the other electrode 14 of the discharge lamp. The remaining two diametrically opposed pair of switch terminals 36, 38 are connected across the other ends of the electrodes 14 by lead-wires 40, 42.

It may be mentioned that the current supply circuit, starting circuit, and starting switch for the lamp, insofar as they have been above described, are conventional and that other standard supply and starting circuits and other starting switches embodying my invention may be employed.

The starting switch 16 comprises a base disc 44 of insulating material from which the terminals 36, 38 project. These terminals, as well as the terminals 30, 32, are adapted to be detachably received in a conventional starting socket (not shown). A tubular shell 46 cooperates with the base disc 44 to provide an enclosure for the operative elements of the switch. A conductor wire 48 connected to the terminal 36 projects upwardly from the base 44 inside of the shell 46. A similarly disposed conductor wire 50 is connected to the terminal 38. Said two wires have angularly disposed portions 52, 54 received in apertures in a partition 56 of insulating material in such manner as to support said partition vertically in the shell 46. Any suitable means, such, for example, as a drop of solder (not shown), adhered on the angularly disposed wire portions 52, 54, may be

employed to rigidly fix the partition. Vertical extensions 58, 60 of the conductor wires 48, 50 on the other side of the partition 56 may serve to receive the operative elements of the switch.

In accordance with my invention, said operative elements comprise two contacts 62, 63 which may consist of horizontally arranged electrically conductive heavy metal wire elements which afford large contact areas and are thus capable of opening a great number of times before they become pitted.

In the illustrated form of my invention, the two contacts 62, 63 are closed when the hand switch 22 is open. It will be understood, however, that when my invention is embodied in other types of switches, these contacts may be disposed in spaced relationship when the hand switch is open.

Pursuant to my invention one of the contacts 62 is carried on the free end of a flat bimetallic strip A of special but simple configuration. The strip is so fashioned and arranged that, upon energization of a heating means associated therewith, the contacts 62, 63 will open. Said strip includes a vertical leg 64 on whose upper end the contact 62 is welded. A second leg 66 is integral with and extends horizontally away from the bottom of the leg 64. A third leg 68, integral with and angularly disposed relative to the leg 66, is welded to the upright wire portion 58 to firmly hold the bimetallic strip A in position.

It will be evident as the description proceeds that the third leg 68 of the bimetallic strip A may be omitted and that, in general, said bimetallic strip should be of such shape as to provide two legs which are relatively angularly disposed, one of the legs being supported and the other leg serving to support a contact.

Also in accordance with my invention, suitable heating means, hereinafter described in detail, are arranged in heat transfer relationship with a leg of the bimetallic strip which is disposed in angular relationship to the leg on which the contact 62 is carried.

By employing this construction I am able to obtain a rapid deflection of the free end of the leg 64 of the bimetallic strip A which carries the contact 62, within a shell 46 of limited height. Such result is achieved because the leg 64, when the leg 66 is heated, swings about the bend connecting the two legs 66 and 68. Thus the contact 62 swings about a center comprising the supporting point of the leg 66 rather than that of the leg 64. In the illustrated example this supporting point is the bend between the legs 66 and 68.

The other contact 63 is supported in any suitable manner. For example, it may be welded to the upper end of a vertically disposed bimetallic strip B whose lower end is secured to the conductor wire portion 60. A feature of my invention is the provision of indentation or offset 69 in the short unbent strip B which points in the direction the strip flexes upon application of heat and thus serves as an indicating symbol to aid an operator in assembly of a switch. The groove may be formed when the straight strip is cut to length.

Preferably both bimetallic strips are so fashioned and arranged that upon a change in temperature arising from any source other than the heating means, both contacts 62, 63 will move in the same direction. This will compensate for changes in room temperature and heating of the switch by the tube 16.

Although any suitable heating means may be employed with the bimetallic strip A to effect the foregoing operation, I prefer to employ a heating means which is so constructed that it can be maintained in close and constant heating transfer relationship to the leg 66 of said bimetallic strip. One such heating means comprises a helical resistance wire heating coil 70 encircling and running longitudinally of said leg 66. One end of the heating coil is welded to a short vertical conductor wire 72 electrically connected to the terminal 32. The other end of the heating coil is connected to a similar conductor wire 74 electrically connected to the terminal 30. The latter end of the heating wire passes through an aperture 76 in the partition 56. The leg 66 is disposed substantially diametrically of the heating coil 70 and said heating coil is sufficiently large so that when said leg 66 is flexed by heat generated by the coil the strip will not touch the coil.

It will be appreciated that by arranging the coil 70 and leg 66 in the foregoing manner, I am able to effect a good heat transfer between said coil and strip which will not be affected by movement of the strip, since as the strip moves away from one segment of the coil, it approaches an opposite segment of the coil.

It may be mentioned that the switch 16 may be disposed in different positions depending upon the position of the receiving socket therefor. It will, therefore, be apparent that, where in the foregoing description various operative elements have been described as arranged vertically or horizontally, these terms are not limitative. The usual condenser 78 is connected across the terminals 36, 38.

The switch operates in the following manner:

When the hand switch 22 is closed, current flows through a low impedance path, including the ballast reactor 24, one of the lamp electrodes 14, switch terminal 36, electrode wire 48, bimetallic strip A, contact 62, contact 63, bimetallic strip B, electrode wire 50, switch terminal 38, other lamp electrode 14, switch terminal 32, resistance coil 70, switch terminal 30, and thence back to the current source. After a short while, which is determined by the time required to heat the electrodes 14 to incandescence and which can be changed by altering the resistance of the coil 70, the heat generated by said coil will cause the bimetallic strip A to flex sufficiently to open the contacts 62, 63. This will break the low impedance series path between the two electrodes 14 and cause surge potential to be applied to said electrodes. If a discharge in the lamp is struck at this time, the lighting current passing through the coil 70 will keep the contacts 62, 63 open. If no discharge is struck, no lighting current will flow through the heating coil, and the coil will, therefore, cool off, permitting the contacts 62, 63 to close after a short time lag. This cycle of actions will be repeated until either the lamp lights or the switch 22 opened.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A starting switch for an electric discharge lamp comprising a pair of contacts, a bimetallic strip including two straight angularly disposed portions, means to support one of said portions, and heating means disposed in heat transfer relationship with said one portion and open to the atmosphere, one of said contacts being carried by the other of said portions, said heating means including a helical resistance coil encircling and running longitudinally of said other portion.

2. A starting switch for an electric discharge lamp comprising a base, a pair of contacts, an L-shaped flat bimetallic strip one of the legs of which is parallel to and supported from said base, a helical resistance coil of low impedance encircling and running longitudinally of said one leg to repetitively open and close the contacts for starting the lamp, one of the contacts being carried by the other leg, and a member to support the second contact from said base.

3. A starting switch for an electric discharge lamp comprising a base, a pair of contacts, a

25

Z-shaped bimetallic strip, the central leg of which is parallel to said base, one of the end legs of said strip being supported from said base, the other end leg of said strip carrying one of the contacts, a helical resistance coil of low impedance encircling and running longitudinally of said central leg to repetitively open and close the contacts for starting the lamp, and a member to support the second contact from said base.

10 5. A starting switch for an electric discharge lamp comprising a base, a pair of contacts, a flat bimetallic strip including two straight integrally connected, adjacent, angularly disposed portions, one of which lies parallel to said base, means to support said one portion from said base, heating means disposed in heat transfer relationship with said one portion to open and close the contacts for starting the lamp, said heating means comprising a helical resistance coil of low impedance encircling and running longitudinally of the portion of the strip parallel to the base, one of said contacts being carried by the other of said portions, and a member to support the second contact from said base.

FRANK P. GASSER.
